United States Patent Office

Des. 211,039
Patented May 14, 1968

211,039

WRIST WATCH

Jerome L. Pinsler, Evanston, Ill., assignor to Marvin Glass
& Associates, Chicago, Ill., a partnership

Filed July 25, 1967, Ser. No. 7,978

Term of patent 14 years

(Cl. D42—8)

Fig. 1

Fig. 2

Fig. 3

Fig. 4

Fig. 5

FIG. 1 is a top plan view of a wrist watch showing my new design;

FIG. 2 is a bottom plan view;

FIG. 3 is an elevational view taken from the bottom of FIG. 1;

FIG. 4 is a right end elevational view thereof; and

FIG. 5 is a left end elevational view.

I claim:

The ornamental design for a wrist watch, substantially as shown.
